Patrick F. O'Reilly, III, LLC

(57) **CLAIM**

The ornamental design for an inverted V-shaped exercise bar, as shown and described.

DESCRIPTION

FIG. 1 is a top-front perspective view of a first embodiment of an inverted V-shaped exercise bar showing our new design;

FIG. 2 is a front elevational view of the embodiment shown in FIG. 1;

FIG. 3 is a top plan view of the embodiment shown in FIG. 1;

FIG. 4 is a rear elevational view of the embodiment shown in FIG. 1;

FIG. 5 is a bottom plan view of the embodiment shown in FIG. 1;

FIG. 6 is a left side elevational view of the embodiment shown in FIG. 1;

FIG. 7 is a right side elevational view of the embodiment shown in FIG. 1;

FIG. 8 is a bottom-front perspective view of the embodiment shown in FIG. 1;

FIG. 9 is a top-front perspective view of a second embodiment of an inverted V-shaped exercise bar showing our new design;

FIG. 10 is a front elevational view of the embodiment shown in FIG. 9;

FIG. 11 is a top plan view of the embodiment shown in FIG. 9;

FIG. 12 is a rear elevational view of the embodiment shown in FIG. 9;

FIG. 13 is a bottom plan view of the embodiment shown in FIG. 9;

FIG. 14 is a left side elevational view of the embodiment shown in FIG. 9;

FIG. 15 is a right side elevational view of the embodiment shown in FIG. 9; and,

FIG. 16 is a bottom-front perspective view of the embodiment shown in FIG. 9.

The broken line portions of the drawing figures are included to show unclaimed subject matter only and form no part of the claimed design.

1 Claim, 10 Drawing Sheets
